A. MANVERS

VACUUM MAKING AND CONDENSING APPARATUS

Original Filed Feb. 11, 1920

UNITED STATES PATENT OFFICE.

ALBERT MANVERS, OF CRICKLEWOOD, LONDON, ENGLAND.

VACUUM MAKING AND CONDENSING APPARATUS.

Application filed February 11, 1920, Serial No. 357,883. Renewed March 20, 1926.

To all whom it may concern:

Be it known that I, ALBERT MANVERS, subject of the King of Great Britain, residing at Cricklewood, London, in the county of

5 Middlesex and Kingdom of England, have invented certain new and useful Improved Vacuum Making and Condensing Apparatus, of which the following is a specification

This invention has for its object a vacuum 10 forming machine designed largely for use in tanning operations, where a large quantity of gas or vapour has to be ejected and yet a very high degree of vacuum obtained.

Figure 1 is a cross sectional elevation of 15 my apparatus and Figure 2 is a sectional plan view of a detail part.

The device comprises a casing 1, having 20 branches with flanged ends 2, (and cap 3 where a branch is not in use) for connection to vessels from which vapour is to be drawn by the vacuum and then subsequently to be condensed.

The water main 4 enters the casing 1 at 25 the top and leads to a ported chamber 5 having discharge passage or ejector pipe 6. The rush of fluid past the ports 7 in the chamber 5 will induce a considerable vacuum within the casing 1, to draw off from any 30 apparatus connected to the branches 2, the vapour to be condensed. This vapour when it has attained the interior of the casing 1 is condensed by a spray, mist, or stream of water or the like from a chamber 8 having a perforated bottom supplied with water 35 by a pipe 9 from the main. The condensate and the stream of liquid from the pipe 6 passes into the pipe 10 at the bottom of the casing 1 which is so disposed relatively to the pipe 6 that the projecting stream of 40 water or the like from the pipe 6 will draw into it the condensate flowing to the base of the casing 1.

The pipe 10 leads into a closed sump 11 right down nearly to the bottom and concentric with the pipe 12. A strong force of 45 the ejected water passing down tube 10 forms a strong ejector at the mouth of the pipe 12 and drives all the water into the pipe so that sump 11 is always empty except

when the apparatus is actually standing. 50 The advantage of having the bend 14 is so as to act as siphon at momentary stoppages of the machine.

It will be obvious that the action of the 55 gush of water from pipe 10 always operates as an ejector in combination with the pipe 12 so as to induce a substantial vacuum in sump 11 and this can be utilized for any 60 desired purpose by connecting any suitable apparatus to the sump 11 through the stop cock 17. The water pipe 4 where it enters the chamber 5 is also preferably provided 65 with a throttling ring 18 having a central hole of a predetermined size with peripheral slots or perforations 19 which will effectively prevent the central hole from becoming stopped up.

I declare that what I claim is:—

1. As a new article of manufacture, a condenser formed of a chamber 1 having a rose 70 over practically its entire area at top, whereby the main volume of steam is condensed and a small ejector in the center of the jet type whereby the air and residual vapor is extracted. 75

2. In combination with a shower condenser and ejector, a discharge pipe from the bottom of the condenser taking the water from both ejector and condenser, a sump into which the discharge pipe enters, and a siphon pipe from the bottom of the sump into which the discharge pipe ejects its water. 80

3. In a vacuum forming device, a chamber 1 having a spray nozzle 8, a central supply pipe 4, a throttling ring 18, a chamber 5 85 surrounding the same having openings 7, an ejector pipe 6, and a conical bottom into which the ejector pipe nearly enters forming an ejector, a discharge pipe 10 therefrom, a sump 11 and a pipe 12 close to the bottom 90 of 10 concentric with it and somewhat larger in diameter whereby a second ejector device is formed at the base of the sump. 95

In testimony whereof, I have hereunto signed my name this 20th day of January 1920.

ALBERT MANVERS.
